(57) **CLAIM**

The ornamental design for a loudspeaker and cradle for electronic device, substantially as shown and described.

DESCRIPTION

FIG. 1 is a perspective view of a loudspeaker and cradle for electronic device in accordance with the present design;

FIG. 2 is an upside down rear perspective view of the loudspeaker and cradle for electronic device shown in FIG. 1;

FIG. 3 is a front view of the loudspeaker and cradle for electronic device shown in FIG. 1;

FIG. 4 is a rear view of the loudspeaker and cradle for electronic device shown in FIG. 1;

FIG. 5 is a top view of the loudspeaker and cradle for electronic device shown in FIG. 1;

FIG. 6 is a bottom view of the loudspeaker and cradle for electronic device shown in FIG. 1;

FIG. 7 is a left side view of the loudspeaker and cradle for electronic device shown in FIG. 1; and,

FIG. 8 is a right side view of the loudspeaker and cradle for electronic device shown in FIG. 1.
